(57) **CLAIM**

We claim, the ornamental design for a display screen or portion thereof with graphical user interface, as shown and described.

DESCRIPTION

FIG. 1 is a front view of a display screen or portion thereof with graphical user interface, showing our new design; and, FIG. 2 is another front view thereof, as shown in a display screen environment.

The evenly spaced broken lines in FIG. 2 illustrate a display screen or portion thereof, and portions of a graphical user interface, and form no part of the claimed design.

The dot dash lines in FIG. 1 and 2 illustrate a display screen or portion thereof, and define the boundary of the claimed design. The dot dash lines form no part of the claimed design.
